(57) **CLAIM**

The ornamental design for a cover for a serving dish, as shown and described.

DESCRIPTION

FIG. 1 is a top, side and front perspective view of a cover for a serving dish showing my new design;

FIG. 2 is a front elevation view, the rear elevation being a mirror image thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a cross-sectional view taken along line 7-7 of FIG. 5; and,

FIG. 8 is a cross-sectional view taken along line 8-8 of FIG. 5.

1 Claim, 3 Drawing SheetsFIG. 1

FIG. 2

FIG. 3

FIG. 4

FIG. 7

FIG. 8
